OBTURATOR FOR PEDIATRIC TRACHEOSTOMY
TUBEGeorge M. Johnson, La Palma, Calif., assignor to Shirley
Laboratories, Inc., Santa Ana, Calif.

Filed Mar. 30, 1973, Ser. No. 346,339

Term of patent 14 years

Int. Cl. D24—03

U.S. Cl. D83—1 K

FIG. 1 is a perspective view showing the top, front and left side of the obturator for pediatric tracheostomy tube; FIG. 2 is a right side elevational view thereof; FIG. 3 is a rear elevational view thereof; and

FIG. 4 is a bottom plan view thereof.

I claim:

The ornamental design for an obturator for pediatric tracheostomy tube, as shown.
